UNITED STATES PATENT OFFICE.

VINCENZO CASSETTA AND FRANCESCO CAPALDO, OF NAPLES, ITALY.

MACHINE-GUN.

1,371,351.

Specification of Letters Patent. Patented Mar. 15, 1921.

Application filed July 9, 1919. Serial No. 309,573.

To all whom it may concern:

Be it known that we, VINCENZO CASSETTA, a subject of the King of Italy, and residing at 15 Via S. Lucia, Naples, Italy, and 5 FRANCESCO CAPALDO, a subject of the King of Italy, and residing at 15 Via S. Lucia, Naples, Italy, have invented certain new and useful Improvements in Machine-Guns, of which the following is a specification, 10 reference being had therein to the accompanying drawing.

This invention relates to machine guns and it has for its object to construct a machine gun which is very simple, robust, 15 light and apt to work in an efficient and reliable manner. These objects are attained more particularly by a novel construction and combination of the ignition and obturation mechanism, also by a new arrangement 20 of the firing means and by the provision of a cooling system for the gun barrel, and by a rational assemblage of the component parts of these devices, as it will hereafter be described with reference to the accompanying drawing which shows, by way of 25 example, one constructional form of the invention.

In these drawings—

Figures 1^a and 1^b show a longitudinal 30 section of the gun with the breechblock in its closed position,

Figs. 2^a and 2^b are a similar view with the breechblock in the open position, while

Fig. 3 shows the cooling means according 35 to the invention, these means not having been shown in the first two figures for the sake of simplicity.

In the drawing, 1 indicates the breech of the gun and 2 is its barrel. Within the 40 breech is slidably mounted a breechblock 3 which is controlled by a coiled spring 4 and is guided by aid of a tooth 5 arranged to slide in a rectilinear slot 6. The slot 6 terminates in a helicoidal notch adapted to cause a 45 short rotary motion of the breechblock at the end of its forward travel and to lock the same when the gun is fired through the frictional resistance produced by it, while it will leave the breechblock free to move rearward 50 after the firing. The breechblock 3 incloses the firing pin 7 which is controlled by a coiled spring 8 and is provided with cylindrical guides 9 and with a rod 10 which projects rearwardly from the breechblock. 55 A hammer 11 is fulcrumed at 12 and has connected with it at 13 a rod 14 which is

secured to a plunger 15 controlled by a spring 16. The head 17 of the hammer 11 strikes against the rod 10 of the firing pin 7 when the breechblock has closed and urges 60 the latter forward to explode the cartridge. When the breechblock recoils after the gun has been fired, it will cause the hammer 11 to rotate downward so as to compress the spring 16. As soon as the breechblock 65 is driven forward again by the action of the spring 4, the hammer 11 bounds upward and its head 17 strikes against the firing pin 7 so as to explode a second cartridge.

18 and 19 indicate openings for the provision of a loader of the stationary type and for the removal of the shells respectively, while 20 is the ejector and 21 the extractor.

The trigger 22 is substantially of U-shape and is located in a recess 23 provided between the handle 24 and the rear end of the breech. The trigger is rotatably mounted at 25 and connected by means of a rod 26 with a bell-crank 27 intended to operate a sear 28 which is fulcrumed at 29 and controlled by a spring 30.

To move the breechblock 3 manually a lever may be employed to act on a lug projecting from the tooth 5 of the breechblock.

To cool the barrel 2, a metal shell 31 is arranged around the barrel (Fig. 3) in spaced relation therewith and extends from the forward end of the barrel until the front part of the breech 1 to which it is secured 90 in any desired or appropriate way. The air space 32 between the barrel and the shell 31 communicates with the outside air through holes 33 provided near the mouth of the barrel and at its rear end with a 95 chamber 34 which houses a fan 35. This fan 35 is caused to rotate by the explosion gases which are conducted from a point of the barrel toward the fan by means of a tube 36. When firing, the explosion gases 100 will cause the fan 35 to work so that it will suck up fresh air from the outside through the holes 33 and this air will pass along the air space 32 and be ejected through a hole 37, whereby the barrel will be efficiently 105 cooled down. It is evident that when the speed of firing grows, the cooling action of the air will be correspondingly increased.

It will readily be understood that the constructional details as above set forth may be 110 varied in many ways without departing from the spirit of the invention.

What we claim is:

1. A machine gun including a breech formed with a chamber, a breech-block mounted in the chamber, a firing pin carried thereby, means in the chamber for closing the breech-block, the breech being formed with a second chamber, a sear mounted therein, a handle mounted on the end of the breech having a recess therein, a trigger mounted in the recess in the handle having an elongated overturned end adapted to conform to the shape of the recess in said handle, connections between the trigger and sear, a hammer mounted in said second-mentioned chamber, means mounted therein for operating the hammer, said means being controlled by the breech-block, and the breech being formed for loading and ejecting whereby when the sear which normally holds the breech-block open is disengaged therefrom, the breech-block will be closed, loading the gun and permitting the hammer to be actuated, the recoil opening the breech, the subsequent operation being by recoil as long as the sear is held out of engagement with the breech-block. 50
2. A machine gun including a breech formed with a breech-block chamber, a breech-block slidably mounted therein, a firing pin mounted in the breech-block, means for closing the breech-block, the breech being formed with a hammer chamber, a hammer pivotally mounted therein, a plunger mounted in the chamber, a spring interposed between the plunger and a portion of the hammer chamber, a link connecting the plunger with the hammer, a sear, and a trigger connected thereto, whereby the sear will hold the breech-block open, said closing means forcing it closed when released from the sear, and being opened by recoil, the spring operating the plunger to cause the hammer to engage the firing pin when the breech-block closes and being compressed by the opening of the breech-block through the hammer and link. 55
3. A machine gun including a breech formed with a breech-block chamber, a breech-block slidably mounted therein, a fir- 60

ing pin mounted in the breech-block, a spring for closing the breech-block mounted in the breech-block chamber, the breech being formed with a hammer chamber, a hammer pivotally mounted therein, a plunger mounted in the chamber, a spring interposed between the plunger and a portion of the hammer chamber, a link connecting the plunger with the hammer, a sear and a trigger connected thereto, whereby the sear will hold the breech-block open, said spring forcing it closed when released from the sear, and being opened by recoil, the second-mentioned spring operating the plunger to cause the hammer to engage the firing pin when the breech-block closes and is compressed by the opening of the breech-block through the hammer and link. 65

4. A machine gun including a breech formed with a breech-block chamber, a breech-block slidably mounted therein, means for closing the breech-block, means for holding said breech-block open, a firing pin mounted in the breech-block, the breech being formed with a hammer chamber, a hammer pivotally mounted therein for actuating the firing pin and adapted to be confined in said chamber, a plunger slidably mounted in the hammer chamber, a link connecting the plunger and hammer, and resilient means mounted in the hammer chamber engaging the plunger and a portion of said hammer chamber whereby the second-mentioned means will hold the breech-block open, the first-mentioned means will close the breech-block when the second means releases it, the hammer being actuated to strike the firing pin by the resilient means through the plunger and link in the closing of the breech-block, said resilient means being compressed in the opening of the breech-block by recoil through the hammer and link. 70
